UNITED STATES PATENT OFFICE.

JOSEPH N. MAHONEY, OF WILKINSBURG, PENNSYLVANIA, ASSIGNOR TO WESTINGHOUSE ELECTRIC AND MANUFACTURING COMPANY, A CORPORATION OF PENNSYLVANIA.

CONTACT MEMBER.

1,199,478.

Specification of Letters Patent. Patented Sept. 26, 1916.

Application filed November 28, 1913. Serial No. 803,517.

To all whom it may concern:

Be it known that I, JOSEPH N. MAHONEY, a citizen of the United States, and a resident of Wilkinsburg, in the county of Allegheny and State of Pennsylvania, have invented a new and useful Improvement in Contact Members, of which the following is a specification.

My invention relates to circuit interrupters for relatively high-voltage circuits, and particularly to the contact members and the mechanism employed in connection therewith.

The object of my invention is to provide an efficient contact device the component parts of which are compactly arranged and the contact portions of which are so constructed as to effect disengagement at a speed which is relatively higher than the speed of the movable contact members.

Circuit interrupters which are adapted to transmit relatively large electric currents at high voltage usually comprise one or more groups of stationary contact members which project downwardly from a suitable support, and a movable bridging contact member to cooperate therewith. In such structures, disengagement of the co-operative contact members is effected when the bridging member is beginning to accelerate. In my present invention, I provide a means whereby disengagement of the stationary and movable arcing contact members is effected at such a time that the movable members of the same have attained a relatively high velocity. I further provide means whereby the speed of separation of the co-operative contact members, is relatively higher than the speed of the moving contact members.

Figure 1 of the accompanying drawings is a sectional elevation of a portion of a circuit interrupter having co-operating stationary and movable contact members constructed in accordance with my invention. Fig. 2 is a side elevational view of a portion of a circuit interrupter embodying my invention; Fig. 3 is an end view, partially in section and partially in elevation, of the contact members embodied in my invention; Fig. 4 is a sectional view taken along the line IV-IV of Fig. 1; Fig. 5 is a sectional view taken along the line V-V of Fig. 3; Fig. 6 is a sectional view taken along the

line VI-VI of Fig. 3, and Fig. 7 is a detail view of the engaging or locking mechanism embodied in my invention.

Referring to the drawings, the mechanism here illustrated comprises, in general, downwardly projecting terminal members 1, and upwardly projecting movable members 2 mounted on each end of a bridging member 3 which is operatively connected to a rod 4 constituting a part of a well known form of circuit interrupter.

The downwardly projecting terminal members 1 severally comprise, in detail, a hollow cylindrical conducting member which is screw threaded to receive a bell shaped member 6. The bell shaped member 6 is provided with a supporting member 7 suitably mounted therein for supporting two tubular members 8. The supporting member 7 has two downwardly projecting portions forming main contact members 9 and an upwardly projecting portion 9^a for guiding a movable conducting member 10. The upper end of the movable conducting member 10 is electrically connected to the terminal member 1 by a flexible strap 11 and a conductor 12, and the lower end has a conducting member 13 attached to it. From the lower side of the conducting member 13 project two arcing contact members 14 that are disposed at the respective sides of a member 15 which has grooves 16 therein, for purposes hereinafter set forth. Each of the tubular members 8 is adapted to receive a helical spring 17 which is attached, at its upper end, to a supporting member 8^a located in the upper portion of the tube 8, and, at its lower end, to the conducting member 13. The arcing contact members 14 are provided, at their lower ends, with removable hexagonal pieces 18, and the main contact members 9 are also provided with removable hexagonal pieces 19 for facilitating renewal should the same become damaged by reason of the arcs which are drawn when the interrupter operates.

The upwardly projecting movable members 2 severally comprise a cup-shaped receptacle 20, suitably screw threaded to receive the bridging member 3 and each is provided with a cover member 21 having a plurality of openings therein and with projections 23 from its under side for sup-

porting a plurality of main movable contact members 24, a plurality of movable arcing contact members 25, and a latching device 26. The main movable contact members 24 are resiliently supported by springs 27 which rest upon the projection 23. The resulting travel of the contact members in an upward direction, by reason of the expansion of the springs 27, is limited by lock nuts 28. The movable arcing contact members 25 are also supported by springs 29 which rest upon the supporting projections 23 that extend from the under side of said cover member 21, as hereinbefore described with reference to the main movable contact members 24. Located between the movable arcing contact members 25 and insulated therefrom, is a cylindrical member 30 having two latch members 31 pivotally mounted upon a projection 32 within the same. The latch members 31 are provided with shoulders 33 against which presses a spring 34 to maintain them normally in their closed positions.

25 The conducting member 10, to which are attached the movable contact members, has a shoulder 35 near its upper end which upon moving downwardly engages the upper end of the guiding member 9^a for limiting the time of effective engagement of the arcing contact members after the main contact members have become disengaged. The tubes 8 are slightly bent in order to centralize them with respect to the terminal members 1, which diverge, for reasons which are well known to those versed in the art.

Assuming the various parts of the apparatus to occupy the position shown in Fig. 1 of the drawing and that the circuit breaker is to be opened, the operation is as follows: Immediately upon the release of a restraining means, (not shown) the operating rod moves downwardly and carries the bridging member 3 and the upwardly projecting movable members 2 therewith. When the movable members 2 travel downwardly, the main movable contact members 24 travel upwardly because of the expansion of the springs 27 a distance which is limited by the lock nuts 28, as hereinbefore explained. When the nuts 28 come into contact with the under side of the projection 23, the main movable and stationary contact members are disengaged. The arcing contact members 14 and 25 which are locked in effective engagement by the grooved member 15 and the latch members 31 travel in a downward direction, as the movable members 2 travel downwardly until the shoulder 35 on the member 10 engages the upper end of the guiding member 9^a which is at such a time, during its movement when the movable members 2 have attained a relatively high velocity, thus preventing further downward movement of the members 10 and causing

the latch members 31 to be disengaged from the grooved member 15 by reason of the downward force of the movable member 2 overcoming the force of the spring 34 which tends to hold the latch members 31 in effective engagement with the grooved member 15. When the grooved members 15 are released, they are drawn upwardly into their normal positions by the springs 17, which have been placed under tension. The movable arcing contact members 25 now assume their normal positions by reason of the expansion of the springs 29 until the lock nuts 22 on the lower end of the movable arcing contact members 25 have reached their limit of travel upwardly.

In the normal open position of the contact device, the plane of the top of the arcing surfaces of the movable members is slightly higher than the plane of the surfaces of the main movable members, for reasons herein-after stated. When the circuit breaker is being closed, the movable member 2 travels upwardly until the arcing contact members effect an engagement, and the movable members 25 move downwardly until prevented from further movement by the springs 29. A relatively short time interval after the arcing contact members effect an engagement, the main contact members are cooperatively engaged and the lower members 24 travel, as did the lower arcing members 25, downwardly until prevented from further movement by the springs 27. Before the lower arcing contact members 25 have reached their limit of travel, the grooved member 15 is effectively engaged by the latch members 31. The difference in level of the planes of the arcing and the main contact surfaces is for the purpose of protecting the main contact surfaces from being pitted and burned.

As will be well understood by those versed in the art, my invention is a decided improvement in contact devices by reason of the attainment of a relatively maximum velocity of the movable contact members before the arcing surfaces are disengaged, and a relatively rapid disengagement of the same, thus reducing the arcing to a minimum.

While my invention is intended for use in circuit breakers for relatively high-voltage circuits, it is not limited to the particular construction illustrated but is capable of various modifications within the scope of the appended claims.

I claim as my invention:

1. A circuit interrupter comprising a contact member having a grooved member thereon, a second contact member having a latch member thereon, the said latch member being adapted to secure the said contact members in engagement when they move in one direction, and means for causing the

latch member to disengage the grooved member when they have moved a predetermined distance.

2. A contact device comprising a stationary member, a movable member, a plurality of main contact members within the said stationary member, a plurality of relatively movable arcing contact members within the said stationary member and having a grooved member thereon; a plurality of main contact members within the said movable member, a plurality of arcing contact members and a latching device within the said movable member, said latching device adapted to normally engage the grooved member to lock the said arcing contact members in effective engagement and for maintaining such engagement until the said movable member has moved a predetermined distance.

3. A circuit interrupter comprising stationary terminal members, movable members, a plurality of main contact members within the said stationary terminal members, a plurality of relatively movable arcing contact members within the said stationary terminal members having a grooved member thereon, resilient means for restraining the movement of the said relatively movable arcing contact members, a plurality of resiliently mounted main contact members supported by the said movable members, a plurality of resiliently mounted arcing contact members and latching devices supported by the said movable members, said latching devices being adapted to engage the grooved members to lock the said arcing contact members in engagement until the said movable members have moved a predetermined distance.

4. A circuit interrupter comprising hollow stationary terminal members, movable members, relatively movable contact members supported within the said hollow stationary terminal members and having grooved members thereon, resilient means for restraining the downward movement of the said relatively movable contact members, a resiliently mounted contact member and resiliently mounted latches supported by the said movable members, said latches being adapted to normally engage the said grooved members to maintain engagement of the contact members until the said movable members have moved a predetermined distance.

5. A contact device comprising stationary terminal members, movable members, a plurality of relatively movable contact members supported within the said stationary terminal members and having grooved members thereon, springs for restraining the downward movement of the said relatively movable contact members, a plurality of contact members operatively connected to the said movable members, means for limiting

the travel of the said relatively movable contact members and latches supported by the movable members and adapted to engage the grooved members for locking the said contact members in engagement until the said movable members have moved a predetermined distance.

6. A contact device comprising stationary terminal members, movable members, a plurality of relatively movable contact members within the said stationary terminal members, springs for restraining the downward movement of the said relatively movable contact members, a plurality of contact members operatively connected to the said movable members, means for limiting the travel of the said relatively movable contact members, grooved members operatively connected to the said relatively movable contact members, and latch members mounted on the movable members for effectively engaging the said grooved members to lock the said contact members in engagement until the said movable members have moved a predetermined distance.

7. A contact device comprising stationary terminal members, movable members, a plurality of relatively movable contact members supported within the said stationary terminal members, springs for restraining the downward movement of the said relatively movable contact members, a plurality of resiliently mounted contact members supported by the said movable members, means for limiting the travel of the said relatively movable contact members, grooved members operatively connected to the said relatively movable contact members, latch members mounted on the movable members for engaging the said grooved members and resilient means for maintaining the said latch members in engagement with the said grooved members.

8. A contact device comprising stationary terminal members, movable supporting members, a plurality of stationary main contact members, a plurality of relatively movable arcing contact members operatively supported by the said stationary terminal members, a plurality of movable main contact members supported by the said movable supporting members, a plurality of movable arcing contact members supported by the said movable supporting members, springs for restraining the downward movement of the said relatively movable arcing contact members, latch members operatively connected to the said movable supporting members, grooved members operatively connected to the said relatively movable arcing contact members, and resilient means for holding the said latch members and the said grooved members in engagement until the said movable supporting members have moved a predetermined distance.

9. A circuit interrupter comprising a stationary member, a movable member, a resiliently mounted contact member supported by the stationary member, a resiliently mounted contact member supported by the movable member, a grooved member operatively connected to the contact member that is supported by the stationary member, and a latch member supported by the movable member and adapted to engage the grooved member to maintain the contact members in engagement until the movable member has moved a predetermined distance.
10. A circuit interrupter comprising a contact member having a grooved member operatively connected thereto, a second contact member having a latch member operatively connected thereto, the said latch member and the said grooved member being adapted to secure the said contact members in engagement when they move in one direction, and means for moving one of the contact mem-
- bers in the opposite direction after they have traveled a predetermined distance.
11. A circuit interrupter comprising a contact member having a grooved member operatively connected thereto, a second contact member having a latch member operatively connected thereto, the said latch member and the said grooved member being adapted to secure the said contact members in engagement when they move in one direction, and a spring for moving one of the contact members in the opposite direction after they have traveled a predetermined distance.

In testimony whereof, I have hereunto subscribed my name this 24th day of Nov., 1913.

JOSEPH N. MAHONEY.
